UNITED STATES PATENT OFFICE.

WALTER H. SMITH, OF PITTSBURGH, PENNSYLVANIA, ASSIGNOR TO MILLER SAW-TRIMMER COMPANY, A CORPORATION OF PENNSYLVANIA.

AUXILIARY GRIPPER.

1,320,345.

Specification of Letters Patent.

Patented Oct. 28, 1919.

Application filed April 3, 1919. Serial No. 287,301.

To all whom it may concern:

Be it known that I, WALTER H. SMITH, a subject of the King of England, residing at Pittsburgh, in the county of Allegheny 5 and State of Pennsylvania, have invented certain new and useful Improvements in Auxiliary Grippers, of which the following is a specification.

This invention relates to sheet grippers 10 for use upon the platen of a platen printing press, during the printing operation.

In platen printing presses it is frequently necessary to use what may be termed auxiliary grippers, which are to be removably 15 and slidably connected with the main grippers, and to include fingers which extend transverse the main grippers to overlie the sheet being printed. Such auxiliary grippers have been heretofore provided, but 20 such constructions necessitate a main gripper of equal width throughout its length in order that the auxiliary gripper may properly fit the main gripper at any point thereof, and such auxiliary grippers have 25 also, to permit their being temporarily secured in adjusted position, been provided with a holding means which permitted more or less objectional play of the auxiliary grippers.

From a structural standpoint the main grippers must have their inner or proximate edges exactly parallel in use, and should taper from their connection with the rocking bar toward their free end. 35 Without such taper the weight at the free end of the grippers is such that the grippers are constantly liable to breakage at or near their juncture with the rocking bar.

The main object of the present invention 40 is therefore to provide an auxiliary gripper which will coöperate with a main gripper of proper tapered form, and which auxiliary gripper is readily adjustable to any position longitudinally of the main gripper, and so coöperates with the main gripper that it will be temporarily locked in an adjusted position and in substantially rigid relation with the main gripper to prevent possible play.

50 In the drawings:—

Figure 1 is a plan of the platen of a press, showing the main grippers thereof constructed in accordance with the present invention and the improved auxiliary gripper in place thereon.

Fig. 2 is an enlarged transverse section on the line 2—2 Fig. 1.

Fig. 3 is a perspective view of one of the auxiliary grippers.

Fig. 4 is a transverse section through a 60 main gripper of a form adapted for co-operation with the improved auxiliary gripper.

The present invention involves the construction of the main gripper, in so far 65 as the same is formed for coöperation with the auxiliary gripper, and also the construction of a particular auxiliary gripper, which while particularly adapted for the type of main gripper described is also capable of use with any and all types of main 70 grippers.

As shown particularly in Fig. 1, the platen 10 of the press carries the usual rocking bar 11, in which the main grippers 75 12 are adjustably secured, as by bolts 13. The main gripper bars here shown are of the best type of elements, wherein their proximate edges 14 are perpendicular to the rocking bar, that is parallel to each 80 other, and the desired taper of such bar, to gradually reduce the weight at the free end, is provided for by inclining the outer edges 15 of such main grippers, as shown.

For the purposes of the present invention 85 each main gripper is formed substantially throughout the operative length thereof with a V-shape depression or channel, one wall 16 of such groove, that is the wall remote from the edge 14 of the gripper, is 90 smooth, while the opposing wall 17 is roughened or serrated. An essential characteristic of this formation is that the V-shape depression extends longitudinally of the main gripper in substantial parallelism 95 with what may be termed the straight edge 14 of such gripper.

The auxiliary grippers are constructed to permit their connection with or disconnection from the main gripper at any point in 100 the length of the latter, and also to permit their adjustment longitudinally of the main gripper following their application. The auxiliary gripper, as more particularly shown in Fig. 3 is preferably constructed 105 of a single piece of metal, and in completed form, comprises a clip made up of an end wall 20, from the lower edge of which and adjacent each end thereof project tongues 19. A bearing plate 21 projects from the 110

upper edge of the wall 20, preferably throughout the length of such wall, in spaced parallel relation to the tongues 19. The tongues 19 have a length approximately corresponding to the minimum width of the main gripper, while the plate 21 has a length equal to the plane portion of the main gripper between the channel and the edge 14. The plate 21, is provided 5 at its edge remote from the wall 20 with what may be termed a locking means for coöperation with the channel and the main gripper. This locking means is provided by bending the material of the plate into 10 a form substantially corresponding to the outline form of the gripper, as at 22, one wall of this V-form being serrated as at 23 to coöperate with the serration 17 in the main gripper channel. The auxiliary gripper 15 per also includes a finger 18, which may be of any desired length, and which forms in reality the paper engaging element. This finger 18 projects from the lower edge of the wall 20, preferably between and in 20 position to the projection of the tongues 19.

The auxiliary gripper may be readily applied to the main gripper by end-wise engagement, or by forcing the auxiliary gripper over the edge 14 of the main gripper at 25 any point in the length thereof. Under either method of application the locking means of the auxiliary gripper will seat in the V-shaped depression of the main gripper, the serrations 23 coöperating with the 30 serrations 17. As thus applied it will be noted that the auxiliary gripper has a firm substantial bearing on the main gripper, the tongues 19 bearing squarely against the lower surface of the main gripper, the wall 35 20 bearing squarely against the straight edge of the main gripper, the plate 21 bearing squarely on the upper surface of the main gripper, while the V-form locking means of the locking gripper is held in the V-shape depression of the main gripper. Under these 40 conditions it is apparent that the auxiliary gripper may be adjusted longitudinally of the main gripper to any desired point in the length thereof, without interrupting in any 45 manner the comparatively rigid bearings described. The coöoperating serrations 17 and 23 will temporarily hold the auxiliary gripper in fixed relation to the main gripper, in any desired adjustment, against casual 50 displacement. The comparatively rigid bearing of the auxiliary gripper with relation to the main gripper absolutely prevents any independent play of the auxiliary gripper with relation to the main gripper, and hence, aside from the longitudinal adjustment 55 the auxiliary gripper is in use substantially a fixed part of the main gripper.

To insure a more substantial locking coöperation between the serrated portions of 60 the main grippers, the non-serrated portion

or wall of the V-form locking means of the auxiliary gripper is arranged at an angle slightly less acute to the horizontal plane of the main gripper, than is the non-serrated wall 16 of the depression in the main gripper, as here shown in Fig. 2. This prevents direct contact between these parts and insures a more binding contact between the serrated portion of the parts.

In Fig. 4, there is shown a form of main 75 gripper 23, wherein the channel is not specifically provided for, while all the advantages thereof are obtained. In this the inner portion of the main gripper is of usual thickness, as at 23', while the outer portion 80 is of reduced thickness, as at 24. The edge of the portion 23 beyond the portion 24, provides the shoulder or wall 25 with which the locking means 22 of the auxiliary gripper may coöperate, and such wall 25 may 85 be serrated, as at 26. This formation permits perfect coöperation between the main and auxiliary grippers.

The improved auxiliary gripper may be placed on the main gripper or removed 90 therefrom at any point in the length of the latter, and does not have to be initially applied at the free end of the main gripper. This is important as additional auxiliary grippers may be added at any time and at 95 any point on the main gripper without disturbing the position or adjustment of auxiliary grippers previously placed.

What I claim is:

1. A main gripper for connection with the 100 gripper bar of a platen, having the side edges thereof tapering toward the free end of the gripper, said gripper being formed with a longitudinally extending wall parallel to one of said edges, in combination 105 with an auxiliary gripper having retaining portions engaging and coöperating with said wall and with the edge parallel to the latter for holding said auxiliary gripper against movement on said main gripper.

2. A platen gripper having one side edge approximately at right angles to the plane of its support and the remaining side edge inclined to such plane, said gripper being formed with a longitudinally extending 115 channel substantially parallel to said right angled edge.

3. In combination, a tapered main gripper for connection with the gripper bar of a platen, having a longitudinally extending 120 wall parallel with one edge and independent of the other, and an auxiliary gripper including a clip for partially embracing said first-named gripper, said clip being provided with retaining means for coöperation with 125 said wall.

4. In combination, a main gripper for connection with the gripper bar of a platen, formed with a longitudinally extending depression parallel with one of its edges, and 130

an auxiliary gripper for slidable engagement with said first-named gripper, said auxiliary gripper having a retaining portion for seating in said depression, said depression and said retaining means having coöperating locking means.

5. A main gripper formed with longitudinally extending V-shape channel, and an auxiliary gripper adapted to slidably embrace the main gripper and having a V-shape section to seat in said channel, said V-shape section and one wall of the channel having coöperating locking means.

6. In combination, a tapered main gripper for attachment to the gripper bar of a platen, said main gripper having a side thereof formed with a longitudinally extending wall parallel with one edge and independent of the other edge, said wall being serrated, and an auxiliary gripper having a serrated portion coöperating with said wall.

7. The combination with a tapered main gripper for attachment to the gripper bar of the platen, formed with a wall parallel with one edge and independent of the other edge, of an auxiliary gripper engaging the edge of the main gripper parallel with said wall, said auxiliary gripper having means associated therewith for engaging said wall.

30 8. The combination with a platen gripper having an edge and a serrated wall parallel with said edge, of an auxiliary gripper having a clip for embracing said platen gripper and a finger projecting from said clip, said clip having a downwardly-extending inclined serrated portion for resiliently engaging the serrations of said wall, thereby to impositively retain said auxiliary gripper

against lengthwise movement on said platen gripper.

9. A tapered main gripper for attachment to the gripper bar of a platen, formed in its upper surface with a depression parallel to one edge, and an auxiliary gripper including a clip bearing against the edge parallel to said depression and on the top and bottom of said main gripper and terminating short of the other edge of said main gripper, and means on the clip to coöperate with said depression to secure the clip in place.

10. In combination, a tapered main gripper for attachment to the gripper bar of a platen, an auxiliary gripper having a gripping portion extending from one edge of said platen gripper, means formed with said auxiliary gripper for frictionally connecting the latter with said platen gripper to admit of adjustment thereon, and means independent of the other edge of the platen gripper and coöperating with the frictional means for releasably maintaining said auxiliary gripper in its adjusted position.

11. The combination with a main gripper for attachment to the gripper bar of a platen, said main gripper having an edge substantially at right angles to said gripper bar and a second edge inclined toward the first, and said main gripper being formed with an intermediate wall parallel with one of said edge walls, of an auxiliary gripper having a portion for coöperation with said wall and a portion for coöperation with the edge parallel to said wall.

In testimony whereof I affix my signature.

WALTER H. SMITH.
